UNITED STATES PATENT OFFICE.

CHARLES ADLER, JR., OF BALTIMORE, MARYLAND.

AUTOMATIC TIME-LIMIT CONTROL MEANS FOR INTERLOCKING LEVERS OF RAILWAY APPLIANCES.

Application filed February 26, 1926. Serial No. 90,733.

This invention relates to improvements in automatic time limit control means for interlocking levers of railway appliances.

The object of the invention is to provide 5 an electrically operated time limit means for ensuring a certain time interval between the successive operation of levers, for example the levers which control respectively, the signal and switch in signal towers, 10 whereby to prevent the throwing of a switch without first giving sufficient warning by signal to the operator of an approaching train.

The present invention includes a novel 15 arrangement of relay with contacts whereby the actuation of the signal lever will cause an operation of the relay that will close a circuit through a motor which latter must operate through a definite time interval before the interlocking means with the switch lever releases the latter for operation.

The invention consists in the novel construction, combination and arrangement of devices hereinafter set forth and specifically 20 claimed herein.

The accompanying drawings illustrate the invention, wherein,—

Fig. 1 shows in a diagrammatic manner, 25 the signal and switch levers; the interlocking device coacting with the switch lever; the improved relay, time-interval motor means, and the circuits for controlling the apparatus.

Fig. 2 illustrates the improved relay and 30 time-interval motor-means employed by me, and

Fig. 3 shows a fragment of the reset lever and the reset finger on the armature when the armature is in the dropped position.

Referring to the drawings the numeral 35 5, designates a signal device; 6, the switch; 7 the signal lever and 8 the switch lever.

The signal and switch levers 7 and 8 may 40 be regarded as located in a tower,—the former being connected to the signal by suitable means, in this instance by rods and cranks 9—10—11 and, the switch lever 8 in this instance, being connected to the switch 45 6 by lever, 12, crank, 13, and rods 14 and 50 15.

The switch lever 8 also has a connection by rod 16 with a lock device 17, so that the

latter must be free to move before the switch-lever 8 itself can be moved.

This lock device 17 is illustrated merely 55 in a diagrammatic manner but will presently be further explained.

These features above are not novel with me and I make no claim to them except in combination with other structures. 60

In carrying out my invention, I provide each signal lever 7 with switch blades 18 and 19 which blades, when the signal lever is in the normal position with the signal at danger, engage switch contacts 20 and 21 65 so as to close with the latter.

The electric switch contact 20 is to control my improved relay while the electric switch contact 21 controls the lock 17 of the switch mechanism through my improved relay. 70

By reference to Fig. 2, of the drawing, the relay mechanism will first be explained followed by an explanation of the circuits.

The relay mechanism is preferably carried in a case or housing 22, in which there 75 is a base 23 of any suitable insulating material.

In actual practice the relay mechanisms will involve numerous electromagnets; front 80 and back contacts and motor mechanisms, but in the present instance, I show but a single set of these devices necessary for the locking of a single switch with the signal which guards that switch.

With this understanding, the numeral 24 85 designates an electro-magnet, which in this instance is shown suspended from the top of the case or housing, and associated with this magnet is an armature 25, which is pivotally sustained from a suitable post or bracket 26, so its free end may be attracted and held up as long as said magnet is energized.

The armature 25, carries an arm 27 which 90 is insulated from the armature and has a front contact 28 and a back contact 29,—the said front contact 28 normally engaging a stationary contact 30 which has connection with a binding-post 31 on the base 23. 95

In this instance, there are also shown contacts 32 and 33 which close when arm 27 is dropped as the relay magnet 24 becomes de-energized. These contacts however are utilized in the system for purposes not in- 100

volved in the operations of the structure herein claimed and a mere mention of them is deemed sufficient.

5 A flexible connection 34 is provided from the arm 27 to a binding-post 35, for a purpose that will presently be explained.

In addition to the contacts referred to, I provide a counterweighted contact-lever 36, which is pivotally carried on short posts 37, 10 which lever lies in the path of the back contact 29, of arm 27 when the latter is dropped with armature 25 as electro-magnet 24 is deenergized.

15 It is to be understood that the post or bracket 26 is so located that the rear end of arm 27, can swing down behind it when the armature is released.

20 A suitable stop 38, is provided for the contact-lever 36 whereby to limit the upward movement of the contacting end toward the back-contact 29 on arm 27.

The rear end of armature 25 is provided with a curved finger or projection 39 that projects rearwardly from the post 26, and 25 this finger projecting as it does at the rear of the armature pivot 40, while the armature is at the opposite side of that pivot, will swing up as the armature itself drops so that when the armature has dropped, it may 30 be swung up by depressing the finger.

This resetting of the armature in my structure is effected automatically through the operation of a motor as will now be explained.

35 The numeral 41 designates a motor which in this instance is presumed to have a horizontal shaft 42 with a worm 43, on the outer end of said shaft.

A worm gear 44, is carried on a shaft 45, 40 which latter is sustained in suitable bearing-supports 46 so that when motor 41 is operated the worm 43, gear 44 and shaft 45 will all be revolved.

The shaft 45, carries a worm 47 and this worm drives a worm-gear 48 which is mounted on a shaft 49 that turns in bearings on posts 50.

The worm-gear 48 therefore drives or revolves the shaft 49 and on this shaft there 55 is a reset-arm 51 which latter will swing through a complete circular path as the worm-gear makes a revolution.

The position of the reset-arm 51 is such that it will swing through the same vertical plane as that in which the trip-finger 39 lies and its function is to engage said finger when the armature has dropped and effect a resetting of the armature after a predetermined time interval delay as will presently be explained.

60 Having described the structural features of the invention, I will now proceed to describe the electrical connections and circuits, reference being made particularly to the dia-grammatic illustration in Fig. 1 of the drawing.

The battery 52, has a connection 53 from one side thereof to one of the electric switch contacts 20 and from the other of said switch contacts 20, there is a wire connection 54, that extends to one side of the electro-magnet 24, of the time interval relay. From the other side of the electro-magnet 24, there are return wires 55 and 56 back to the other side of the battery 52.

70 It will therefore be seen that when signal lever 7 is in the normal position with the signal 5 at danger, the switch blade 18 will close the switch contacts 20 and maintain a closed circuit from battery 52, through the switch contacts and the electro-magnet 24, of the relay,—thereby keeping said relay magnet energized.

75 From battery 52, there is another normal circuit which is controlled by the armature 25 of relay magnet 24 to operate the lock 17 of the rail switch lever 8, as will now be explained.

80 From battery 52, by wire 57 to binding post 31 on the relay, then by wire 58 (see Fig. 2) to a contact bar 59 of said relay on which the contact 30 is located, then through front contact 28 of armature-arm 27 to and through wire 34 and binding post 35; then from binding post 35 by wire 60 to one of the switch contacts 21; then by wire 61 to lock-magnet 62 and from said lock-magnet by wires 63, 64 and 56 back to the battery 52.

85 It will therefore be understood that when the signal lever 7 is in the normal position (signal at danger) and relay magnet 24 is energized, the lock-magnet 62 will also be energized so as to hold latch 65 up and free the lock 17 in order that the rail switch lever 8 may be moved.

90 The rail switch-lever 8 may therefore be moved when the signal 5 is at danger and signal lever 7 is in the normal position, except, that after the rail switch and signal have once been set for an approaching train and it is desired to change the route of that train, then the switch cannot be changed until 1st, the danger signal is set against the approaching train and 2nd, a predetermined time-interval must pass after that danger signal has been set, as will presently be more fully explained.

95 By reference to Fig. 2 of the drawing, it will be seen that a wire 66 extends from wire 54, to the back contact 29 on armature-arm 27 and it will further be noted that a wire 67 leads from post 37 and counterweighted contact-lever 36, which wire 67 connects with one side of the relay-motor 41.

100 It will further be seen that from the other side of relay motor 41 there is a wire 68 which leads to a binding post 69 on the relay base. From this binding post 69, there is a wire 70 which preferably passes through a resistance adjuster 71 and from the resistance adjuster, there is another wire 72,

which connects in this instance with return wires 63—64 and wire 56 leading back to the battery 52.

Operation.

5 The operator will first set the rail switch 6 by moving switch lever 8 to the broken line position in Fig. 1, and in doing this, the rod 16 will be actuated and the lock 17, 10 will be moved until the lug 72 thereon will swing to a position to the left of the latch end 73 of the latch 65, which is held up by the lock-magnet 62.

Having set the rail switch 6, the operator 15 then moves lever 7 to set the signal 5 to clear. This shifts lever 7 from the normal danger position to the broken line position shown in Fig. 1, and in doing this both switch-blades 18 and 19 are withdrawn from 20 the contacts 20 and 21 and thereby opening the circuit through the relay magnet 24, and at the same time opening the circuit through the lock magnet 62.

The opening of the lock-magnet circuit at 25 once deenergizes that magnet 62 and allows latch 65 to drop and as lock 17 will then have been swung over to the left, the latch-end 73 will drop in front of lock lug 72 and prevent the lock from being swung back, 30 consequently rail switch-lever 8 must remain in the left hand position as long as lock-magnet 62 is deenergized.

When the signal lever 7 was moved and the circuit interrupted at 18—20, relay magnet 24 became deenergized and armature 25, with its arm 27 both dropped. The dropping of arm 27 produced a break at its front contact 28 and thus created a second break in the circuit through the lock-magnet 62, (the 40 first break being at the contacts 21) so that even if the signal lever were at once returned and blade 19 made to close the contacts 21, the lock magnet would not be energized because armature 25 and arm 27 are down.

When this armature 25, is dropped, its movement carries it beyond the influence of relay-magnet 24 so that even if that magnet 24 is again energized, it will not pick up the armature 25 and its arm 27. Therefore as long as arm 27 is down the lock magnet 62 cannot be energized, consequently the rail switch lever 8 cannot be moved until two things take place, to wit: the signal lever 7 55 must be returned to danger and the signal thus set and second after the signal has been returned to danger, then there must be a predetermined time interval delay before the switch lever can be unlocked and the rail switch moved.

The purpose of this delay is to prevent the operator from suddenly changing his mind about routing a train without first setting the signal at danger long enough to 60 give the engineer time to stop his train be-

fore reaching the switch which might otherwise be open.

This time interval is determined by the relay motor 41, which begins a cycle of motion when the signal lever 7 is returned to 70 normal or danger because at that time the armature 25 and its arm 27 are down and cannot be picked up by relay magnet 24, although the latter becomes energized when the signal lever 7 is returned and the blade 75 18 closes the circuit between contacts 20, the battery and said relay-magnet.

When the signal lever 7 is returned and blade 18 closes the contacts 20, the relay magnet 24 becomes energized and at the 80 same time a branch circuit is formed from the wire 54, to back contact 29, through counterclockweight contact 36, to wire 67 then through the motor to drive the latter and back by wires 68—70—64 and 56 to battery.

The motor having started the reset arm 51 begins to travel slowly through a circular path and after a predetermined time, it approaches the upwardly-inclined trip finger 90 39 of the armature which then has the position shown in Fig. 3 of the drawing, which is in the path of the reset arm.

As the reset arm 51 therefore engages the finger 39 and depresses the latter, it swings 95 armature 25 up until the latter comes within the range of the relay magnet 24 whereupon the magnet will quickly attract the armature and cause the finger 39 to swing quickly out of the path by the reset arm 51.

Immediately upon the armature closing contacts 28—30 the circuit through the motor will be opened and the motor then stop, leaving the reset arm 51 in readiness for another cycle of operation.

It will be noted that as the armature 25 and its arm 27 are slowly resetting the counterweighted contact 36 is following the arm up and the contact 36 ceases to move up just as the magnet 24 attracts the armature.

When the armature is picked up then the lock circuit through the front contacts 28—30 is closed and lock magnet 62 becomes energized and lifts latch 65, thereby releasing the lock and permitting the switch lever 8 115 to be moved and the rail switch 6 thus reset.

Having described my invention, I claim,—
1. In a railway signal and switch apparatus the combination with a switch operating mechanism, of a lock including a latch for holding the switch mechanism, a lock-magnet for controlling the latch a relay magnet having an armature coacting therewith which latter when the relay is de-energized moves beyond the influence of the relay magnet to pick it up, a circuit controlled through the signal mechanism to normally energize the relay-magnet, a motor mechanism with means for moving the armature to a position where the relay magnet 125 130

may pick it up, and electrical circuits controlled by the signal mechanism when the latter is moved to the danger position for setting the motor mechanism into operation and at a predetermined time releasing the lock to permit the switch mechanism to be moved.

2. In a railway signal and switch apparatus the combination with a switch operating mechanism, of a lock including a latch for holding the switch mechanism, a lock-magnet for controlling the latch, a relay including a magnet having an armature with front and back contacts said armature moving when the relay is deenergized to a position beyond the influence of the relay magnet, a circuit controlled through the signal mechanism and front contact of said armature to normally energize the relay-magnet, a motor mechanism with means driven thereby for moving the armature to a position within the influence of the relay magnet and electrical circuits controlled by the signal mechanism when the latter is moved to danger position said circuits including the back contact of the armature for setting the motor mechanism into operation and after a time interval moving the armature within the influence of the relay and energizing the lock-magnet to release the switch mechanism.

3. In a railway signal and switch apparatus the combination with a switch operating mechanism, of an electrically-operating lock for holding the switch mechanism, a signal operating mechanism, a relay including a magnet having an armature with front and back contacts, a motor mechanism associated with the relay with means driven by the motor for resetting the said armature, circuit closers operated by the signal mechanism, a circuit including one of said cir-

cuit-closers and the relay to hold said armature raised, another circuit including another of said circuit-closers the front contact of the armature and the electrically-operated lock to release said switch operating mechanism and a circuit including the back contact of the armature and the motor when the armature is down, the switch is locked and the signal has been returned to a danger position to raise said armature to normal position.

4. In a railway signal and switch apparatus the combination with a switch-operating mechanism, of an electrically-operated lock for the said switch mechanism, a signal-operating mechanism, two circuit-closers operated by the signal mechanism and both being closed when the signal is at danger, a relay including a magnet and an armature which latter carries means providing front and back contacts the armature being mounted so that when dropped by the de-energization of the magnet it will move beyond the influence of the magnet to pick it up again, a motor, time operated means moved by the motor to move the armature back to a place where the relay magnet may pick it up, a circuit including one of the circuit closers operated by the signal mechanism and also including the relay-magnet, another circuit including the other of said two circuit-closers the front contact of the relay armature and the electrically-operated lock of the switch mechanism and a third circuit including the first of said two circuit-closers, the back contact of the armature and the motor said third circuit being formed when the signal has been returned to the normal danger position and the switch is still in the operated position.

In testimony whereof I affix my signature.
CHARLES ADLER, JR.
